UNITED STATES PATENT OFFICE.

THOMAS R. COOK AND CHARLES L. FISCHER, OF PITTSBURGH, PENNSYLVANIA.

APPARATUS FOR DETERMINING FLANGE-PRESSES.

1,219,922.

Specification of Letters Patent.

Patented Mar. 20, 1917.

Application filed July 20, 1914. Serial No. 852,119.

To all whom it may concern:

Be it known that we, THOMAS R. COOK and CHARLES L. FISCHER, both citizens of the United States, residing at Pittsburgh, 5 in the county of Allegheny and State of Pennsylvania, have invented certain new and useful Improvements in Apparatus for Determining Flange-Pressures, of which the following is a specification.

10 The invention relates to testing apparatus for determining the pressures between the flanges of the wheels of cars and the heads of the rails upon which the wheels ride. The apparatus as hereinafter described is designed to be applied and operated at varying speeds over the roads, to ascertain the flange pressures under exact working conditions. The apparatus will preferably be used on experimental track 20 with different types of rail heads and different contours of flanges to ascertain the pressure in connection with different vertical loads which will cause a flange of a given contour to mount a rail head of a given contour. Certain embodiments of 25 the preferred apparatus are illustrated in the accompanying drawings, wherein—

Figure 1 is a transverse section through a truck equipped with our improved apparatus; and Fig. 2 is a side elevation of the track of Fig. 1.

Referring to Figs. 1 and 2; 1 is the body bolster upon which the car body 2 is mounted; 3 and 4 are the rails carrying 35 the wheels 5 and 6 secured to the axle 7 in the usual way; 8 and 9 are the frame members secured to the body bolster; 10 and 11 are brasses mounted for movement longitudinally of the axle 7, and 12 and 40 13 are boxes carrying the said brasses.

Opposite the ends of the axle are the thrust bearing blocks 14 and 15, antifriction balls 16 being interposed between such ends and the blocks. The parts are so proportioned that when the blocks 13 and 14 engage the brasses 10 and 12 the axle has a slight longitudinal play. Interposed between the ends of the boxes and the bearing blocks are the springs 17 and 18, the 50 tension of which is adjustable by means of the screws 19 and 20.

The boxes are slotted as indicated at 20 and 21, and arms 22 and 23 carried by the bearing blocks project upwardly there- 55 through. These arms are provided with fingers 24 and 25 adapted to register upon

the paper of indicating apparatus 26 and 27 which may be of any approved type. Sufficient space is provided between the wheels and boxes at 28 and 29 to permit of 60 the lateral movement of the boxes with respect to the axles.

It will be readily understood that the foregoing apparatus is adapted to register the lateral pressure of the wheel flanges 65 upon the heads of the rails. For instance when a force tends to move the car body 2 and bolster 1 to the left (Fig. 1) this force is transmitted to the frame 9 and thence to the box 13, tending to move it 70 to the left. This movement compresses the spring 18 and pressure is transmitted through the bearing block 15, the axle 7 and the flange of the wheel 5, to the head of the rail 3. The extent of this movement depends upon the force, and this movement is registered on the apparatus 27 by reason of the arm 23 and finger 25. The extent of the force necessary to derail the car can be thus readily determined upon 75 test. The apparatus at the other end of the axle similarly registers the force exerted between the flange of the wheel 6 and the rail 4 when the car body is moved to the right.

80 What we claim is—

1. The combination with an axle provided with a pair of flanged wheels, a truck carried by the axle and mounted for lateral movement with respect thereto, yielding 90 means for restraining such movement, and means for indicating the pressure exerted by the truck as it moves laterally with respect to the axle.

2. The combination with an axle provided with a pair of flanged wheels, a truck carried by the axle and mounted for lateral movement with respect to one of the wheels, yielding means for resisting 95 such movement, and means for indicating the pressure exerted by the truck in its tendency to move laterally.

3. The combination with an axle provided with a pair of flanged wheels, a truck carried by the axle and mounted for lateral movement with respect to one of the wheels, yielding means for resisting such movement, and an indicator for showing 100 the extent of such lateral movement against the resistance of the said yielding means.

105 4. The combination with an axle pro-

vided with a pair of flanged wheels, a truck carried by the axle and mounted for lateral movement with respect thereto, yielding means for restraining such movement in both directions, and indicating means for showing the extent of the lateral movement in both directions.

5. The combination with an axle provided with a pair of flanged wheels, a truck carried by the axle, a bearing box carried by the truck and mounted on the axle for lateral movement, yielding means tending to prevent relative lateral movement of the box and axle, and means for 10 indicating the extent of such movement.

6. The combination with an axle provided with a pair of flanged wheels, a truck carried by the axle, a bearing box carried by the truck and mounted on the 15 axle for lateral movement, a thrust bearing

and a spring between the box and the axle, and means for indicating the extent of such movement.

7. The combination with an axle provided with a pair of flanged wheels, a truck carried by the axle, a bearing box at each end of the axle mounted for movement therealong, a thrust bearing and a spring between each box and the end of the axle, and means for indicating the relative movement of each box with respect to the axle.

20 In testimony whereof we have hereunto signed our names in the presence of the two subscribed witnesses.

THOMAS R. COOK.
CHAS. L. FISCHER.
